Hanson & Brooks, LLP

(**) Term: **14 Years**

CLAIM

(21) Appl. No.: **29/218,763**

I claim the ornamental design for a combined travel steam
iron with brush or similar article, as shown and described.

(22) Filed: **Dec. 7, 2004**

DESCRIPTION

(51) **LOC (8) Cl. 07-05**

FIG. 1 is a top perspective view of a combined travel steam
iron with brush or similar article, showing my new design;

(52) **U.S. Cl. D32/70; D32/71**

FIG. 2 is a left side elevational view thereof;

(58) **Field of Classification Search** D32/68-72;

FIG. 3 is a right side elevational view thereof;

38/69, 77.1-77.9, 74-75, 77.81, 90-97; 219/245-248
See application file for complete search history.

FIG. 4 is a top plan view thereof;

(56) **References Cited**

FIG. 5 is a bottom plan view thereof;

U.S. PATENT DOCUMENTS

FIG. 6 is a front elevational view thereof;

4,366,367 A * 12/1982 Mazzucco 392/335
D284,798 S * 7/1986 Doyel D32/69
4,688,340 A * 8/1987 Ostrellich 38/90

D340,330 S * 10/1993 Seguljic D32/70
D360,509 S * 7/1995 Maeda et al. D32/70

FIG. 7 is a rear elevational view thereof;

FIG. 8 is a top plan view thereof, in an alternate position,
with the handle pivotally turned outwardly;

FIG. 9 is a top plan view thereof, with the handle removed
for clarity of disclosure;

FIG. 10 is a bottom plan view of the handle thereof, shown
separately for clarity of disclosure; and,

FIG. 11 is a bottom perspective view thereof, with a brush
attached thereto.
